UNITED STATES PATENT OFFICE.

NORRIS G. MORGAN, OF GALVA, ILLINOIS.

GRADING APPARATUS.

Application filed December 5, 1925. Serial No. 73,330.

This invention relates to a grading apparatus and more particularly to a screening device for grading seed corn.

It is an object of this invention to provide 5 compact screening means for efficiently screening seed corn as to size of kernel.

It is a further object of this invention to provide a grading apparatus comprising a plurality of screening compartments super- 10 posed one above the other wherein the screening is accomplished by means of vertical screening plates.

It is a further object of this invention to provide a grading apparatus for seed corn 15 comprising a vertical screening means provided with a lateral shaking mechanism and means for preventing the screening means from becoming clogged.

Other and further important objects of 20 this invention will be apparent from the disclosures in the specification and the accompanying drawings.

This invention (in a preferred form) is 25 illustrated in the drawings and hereinafter more fully described.

On the drawings:

Figure 1 is a top plan view of a grading apparatus embodying the principles of my invention.

30 Figure 2 is a broken sectional view taken on line II—II of Figure 1.

Figure 3 is a sectional view taken on the line III—III of Figure 1.

35 Figure 4 is a broken top plan view of a modified form of my invention.

Figure 5 is a side elevational view of the device shown in Figure 4, with parts broken away and in section.

As shown on the drawings:

40 The reference numeral 1 in Figures 1 to 3 inclusive indicates a supporting frame comprising corner posts 2, side bars 3 and 4 and end bars 5 and 6. Parallel with the side bar 4 there is mounted a driving shaft 7 supported in bearings 8 from the posts 2. At 45 one end of the shaft 7 there is secured thereto a driving pulley 9 run from any suitable source of power. An eccentric rod 10 is se-

cured to the shaft 7 intermediate its ends and connected by means of a connecting rod 11 to a suspended frame or cradle 12. Said frame 12 is suspended from the bars 5 and 6 by means of relatively flexible angle rods 13. The frame 12 is rectangular in shape and formed of side bars 14 and 15 and end bars 16 and 17 joined therewith. The angle rods 13 are swiveled at their respective ends to the bars 5 and 6 and to the frame end bars 16 and 17 to allow the frame 12 to be shaken laterally by means of the crank 10 and connecting rod 11, said rod 11 being pivotally secured to the side bar 15 of said frame 12.

A screening mechanism 18 is supported 50 by means of the suspended frame 12 and comprises a narrow rectangular shaped box, suitably formed of sheet metal and extending substantially the height of the supporting frame 1. One end of said screening mechanism 18 is provided with a flaring 55 spout 19 into which the material to be graded may be poured. The other end of said screening mechanism 18 is formed into a bottom discharge spout 21, said spout being 60 bolted to the end bar 17. Said ends as 65 well as the top and the bottom of the screening mechanism 18 are imperforate, but the sides 21 thereof are provided with parallel 70 rows of perforations 22 extending substantially the length of the sides. Dividing successive sets of perforations 22 are a plurality of parallel spaced imperforate partitions 23 extending horizontally between the sides 21 to which they are secured by lateral flanges 24. Said partitions 23 as well as the 75 bottom of the screening mechanism 18 are preferably inclined from the intake spout end downwardly toward the discharge end. Brace rods 25 extend from the ends of the bars 16 and 17 to the top of the screening 80 mechanism 18 to rigidly brace the same.

A pair of spaced longitudinal guide rails 85 26 extend between the bars 5 and 6 to which they are attached on each side of the spout 19. A block 27 is mounted for sliding movement upon said guide rails 26 and is provided 90 95

with a plurality of rods 28 depending from its under side adjacent each side of the screening mechanism 18. Said rods 28 being freely suspended from the block 27 are 15 adapted to knock against the sides 21 of the screening mechanism when the same is shaken laterally for the purpose of dislodging any material that may become lodged in the perforations 22. Arrangement is made for sliding the block 27 in the guide rails 26, comprising a link chain 29 driven over sprockets 30 and connected to said block by means of a rod 31. Said sprockets 30 are shown mounted on the ends of their 20 respective shafts 32 and 33, said shafts in turn being supported in bearings 34 and 35, respectively, from the side bar 4 and a second bar 36 parallel thereto. The shaft 33 is provided with a pulley 37 which may be driven by any suitable source of power.

In the modified form of my device shown in Figures 4 and 5 the screening mechanism instead of being suspended from the top of the supporting frame and shaken laterally, 25 is pivotally mounted at the spout end and shaken through an arc from the other end. There is shown a supporting frame 40 in general similar to the frame 1 described, to one end of which is pivotally mounted a 30 screening mechanism 41 by means of hinges 42. The other end of said screening mechanism 41 is connected to a shaking mechanism 43. Said shaking mechanism 43 comprises a driven pulley 44 secured to a stub shaft 45 on which is mounted a disk 46 carrying an eccentric pin 47. A connecting link 48 is pivotally connected at its ends to said eccentric pin 47 and to a lug 49 secured to the screening mechanism 41. It is thus 40 apparent that as the disk 46 is revolved, the screening mechanism 41 is oscillated to and fro in the arc of a circle. The screening mechanism 41 is in general similar to that already described.

45 The operation of my grading apparatus is substantially as follows:

The material to be graded is dumped into the receiving spout 19 either continuously or in small quantities from time to time. 50 The particular material for which my apparatus has been designed is seed corn, but it is obvious that the apparatus is adapted to be used in grading other material. The advantage of grading seed corn lies in the 55 fact that the value of the seed corn depends in large measure upon the size of the kernels, the larger kernels being of greater value. The material to be graded, which we 60 may assume by way of example to be corn, falls by gravity into the lowermost screening compartment and when that is filled, said material enters the successively higher compartments. The laterally shaking movement imparted to the screening mechanism 65 is sufficient to throw the kernels of

corn against the perforated side plates 21. Since the perforations 22 are of such suitable size as to allow the smaller of the kernels to pass through, separation of these smaller kernels takes place. The larger kernels gradually find their way by gravity down to the discharge spout end of the screening mechanism and are discharged through the spout 20. The smaller screened out kernels on the other hand are separately 70 collected as they fall through the holes 22. To provide against these smaller kernels from being stuck in the perforations 22, the rods 28 are adapted to move lengthwise 75 of the screening mechanism 18 and tap the sides 21 of said screening mechanism as the same is shaken from side to side.

If desired the action of my grading apparatus may be supplemented by the provision of means for subjecting the material to be graded to a blast or current of air 80 whereby the lighter weight material or part thereof is removed.

It is thus seen that I have provided a 85 compact grading apparatus for efficiently grading various materials and more particularly seed corn.

I am aware that many changes may be 90 made, and numerous details of construction 95 may be varied through a wide range without departing from the principles of this invention, and I therefore do not purpose limiting the patent granted hereon, otherwise than necessitated by the prior art.

I claim as my invention:

1. A device of the class described comprising a supporting frame, a relatively deep and narrow screening box supported therefrom and having a top inlet spout at one end and a bottom discharge spout at the other end, the sides of said box being perforate, means for laterally reciprocating said box, and partitions for dividing said box into successive longitudinally disposed compartments, all of said partitions similarly terminating short of both ends of the box and all of said compartments similarly communicating at their opposite ends with said top inlet and bottom discharge spout.

2. A device of the class described comprising a supporting frame, a shaking frame suspended therefrom, a screening mechanism mounted on said shaking frame and having perforate vertical sides, means for imparting reciprocating lateral movement to said shaking frame and means adapted to be contacted by said screening mechanism due to the lateral movement thereof for preventing the vertical screen members from becoming clogged.

3. A grading apparatus including a screening box having perforate side walls, means for imparting lateral reciprocating movements to said box, and means spaced from the sides of the box adapted to be

contacted by the box sides in its movements, to prevent clogging of the perforations thereof.

4. A grading apparatus including a screening box having perforate side walls, means for imparting lateral reciprocating movements to said box, means spaced from the sides of the box adapted to be contacted

by the box sides in its movements, to prevent clogging of the perforations thereof,¹⁰ and means for shifting said last-named means lengthwise of the box during reciprocating movements of the box.

In testimony whereof I have hereunto subscribed my name.

NORRIS G. MORGAN.
